UNITED STATES PATENT OFFICE.

THEODOR HEMBERGER, OF ST. LOUIS, MISSOURI.

MUSICAL DRUM.

No. 899,488.

Specification of Letters Patent.

Patented Sept. 22, 1908.

Original application filed December 24, 1907, Serial No. 407,906. Divided and this application filed March 9, 1908.
Serial No. 419,980.

To all whom it may concern:

Be it known that I, THEODOR HEMBERGER, a citizen of the United States, residing at the city of St. Louis, State of Missouri, have 5 invented a certain new and useful Improvement in Musical Drums, of which the following is a specification, reference being had to the accompanying drawings, forming part of this specification, this application being a 10 division of my former application for patent for drums, filed December 24, 1907, Serial No. 407,906.

In the drawings Figure 1 is a top plan view of a drum embodying my invention, 15 portions thereof being broken away to more clearly show certain details of construction; Fig. 2 is a side elevational view, partly in section, of said drum; Fig. 3 is a fragmentary detail sectional view of the drum-head; 20 Fig. 4 is a fragmentary detail sectional view, somewhat enlarged, of my drum; and Fig. 5 is a fragmentary detail sectional view of one of the clamping rings used on my drum.

This invention relates to a new and useful 25 improvement in musical drums.

Heretofore, so far as I am aware, in the manufacture of musical drums the vellum or skin heads are placed while wet on the body or shell portion of the drum and allowed to 30 stretch and dry thereon, being held in position by a clamping ring. Should a head afterwards become worn or broken, it takes some time to remove the broken or worn head and replace the same with a new one. 35 Also, in tuning the heads of drums now on the market, the tension of both heads is regulated simultaneously, and as the heads usually vary considerably as to quality, it is very difficult and also takes considerable 40 time to regulate the tension of, or tune, said heads properly.

The objects of my invention are, therefore, broadly, to provide a drum with interchangeable heads which can be readily removed whenever necessary or desired and new heads easily and quickly placed in position and to provide a drum with heads which can be tuned separately and independently.

With these objects in view, my invention 50 consists in the novel construction, arrangement, and combination of the several parts, all as will hereinafter be described and afterwards pointed out in the claims.

In the drawings, 1 indicates the hollow 55 cylindrical body portion or shell of the drum, on the ends of which are adapted to be

mounted the heads 2 and 3, respectively. As the head 3 is similar to head 2, the description of head 2 will also be applicable to head 3. The drum-head 2 consists of a ring or frame 2^a (see particularly Fig. 3), preferably of aluminum, around which the skin or vellum portion of the head is folded while wet and allowed to stretch and dry thereon, said ring forming a retaining or supporting frame 60 for said skin or vellum. The edge of the skin or vellum is brought some little distance over and around said ring, as shown in Fig. 3, so as to provide a hem, in order that when the head is in position on the body portion of the 65 drum and tension is applied thereto by means of the securing devices hereinafter described, the said skin portion will not pull off from around said ring. These drum-heads, consisting of said supporting ring and the skin or vellum portion stretched thereon, 70 are made entirely distinct and separate from the drum proper and can be made in any quantity, so that in the event of a head becoming broken or worn, it can be readily removed, as hereinafter described, and a new 75 head quickly placed in position. In order that the supporting-ring 2^a will not be pulled out of shape by the shrinkage of said skin portion in drying, and also in order to prevent 80 any corroding or wearing of said skin portion by said ring, which would occur were said ring of iron or some similar metal liable to rust, said ring 2^a, as stated, is preferably made of aluminum or some other similar 85 metal which does not rust and which is, at the same time, strong enough to resist the shrinking force of said skin portion. The 90 edges of the body portion or shell 1 are preferably folded inwardly, as at 1^a, to form a rounded, smooth edge, which will not injure or cut the drum-heads 2 and 3 when in position 95 thereon, the folding-in of said edges also serving to stiffen said body portion. Over 100 said heads 2 and 3 are designed to be placed clamping-rings 4 and 5, respectively. Rings 105 4 and 5 are substantially U-shaped in cross-section, the inner flanges thereof, which rest upon and bear against the said heads, being preferably roughened or knurled, as at 5^a, Fig. 5, so as to securely grip the edges of said heads. 2 and 3. The outer flanges of said rings 4 and 110 5 are provided to avoid a sharp edge which the base webs of said rings would otherwise present. Around said body portion 1 and a short distance from the top and bottom thereof are rings 6 and 7, in the form prefer-

2
ably of angle-irons, which are riveted to said body portion 1, as shown in Figs. 2 and 4. The horizontal flanges of said rings 6 and 7 are provided with threaded openings to receive securing-screws 9 fitting in perforations or openings in the rings 4 and 5, the screws 9 being preferably provided with angular or square heads, so that they may be readily adjusted. By this construction, the tension of the drum-heads is readily adjusted or regulated by tightening or loosening said screws 9, the knurled or roughened edge of the clamping-rings 4 and 5 firmly gripping said heads and stretching the same evenly and smoothly, the greater the tension of said heads the louder and clearer the tone of the drum. As there is a clamping-ring for each drum-head with a separate set of adjusting or securing-screws 9 therefor, each drum-head can be easily and quickly tuned or stretched independently of the other, and the said heads, being of the same construction, can also be used interchangeably. As will also be readily seen, should a head become broken or worn, it can be quickly removed by loosening the screws 9 and clamping rings 4 or 5, and a new head easily placed in position, this operation requiring but a very short space of time.

30 I prefer to make my drum of aluminum or other light material, so that, while the weight thereof is not greater than that of other drums with which I am familiar, the same is rendered very durable and will not be injured or damaged by any rough usage to which it may be subjected.

Having thus described my invention, what I claim and desire to secure by Letters Patent is:

- 40 1. A head for musical drums or similar musical instruments, the same consisting of a retaining-ring and a skin portion stretched over the area of said ring on the plane of the top edge thereof, the edge of said skin portion being brought around and inclosing said ring and then folded back upon the said skin portion within the circumference of said ring; substantially as described.
2. A head for musical drums or similar musical instruments, the same consisting of a metallic retaining-ring and a skin portion stretched over the area of said ring on the plane of the top edge thereof, the edge of said skin portion being brought under and around said ring and then folded back over said ring and upon the skin portion within the circumference of said ring; substantially as described.
3. In a musical drum, the combination with a cylindrical body portion, of a re-

movable drum - head therefor, said drum-head consisting of a retaining-ring adapted to impinge and fit closely around the top of said body portion and a skin portion stretched across the area of said ring, the edge of said skin portion being brought around and over said ring and then folded back, in the form of a hem, to within the circumference of said body portion and upon said skin portion within the circumference of said ring, and means adapted to rest and bear upon said hem for removably securing said ring in position on said body portion; substantially as described.

4. In a musical drum, the combination with a cylindrical body portion, of a removable drum - head therefor, said drum-head consisting of a retaining-ring adapted to impinge and fit closely around the top of said body portion and a skin portion stretched across the area of said ring, the edge of said skin portion being brought around and over said ring and then folded back, in the form of a hem, to within the circumference of said body portion and upon said skin portion within the circumference of said ring, a clamping-ring adapted to rest on said retaining-ring and to impinge upon said hem, a laterally - extending flange around said body portion, and screws passing through said clamping-ring and into said flange for removably securing said drum-head in position and regulating the tension of the skin portion thereof; substantially as described.

5. In a musical drum, an aluminum cylindrical body portion, a removable drum-head therefor, said drum-head consisting of an aluminum ring fitting around the outer edge of said body portion and a skin portion stretched across said ring, the edge of said skin portion being brought around and over said ring in the form of a hem, a U-shaped clamping ring for removably holding said drum-head in place, the inner flange of said clamping ring bearing on the ring portion of said head over said hem, an aluminum ring of angle-iron shape secured to said body portion, and screws passing through said clamping ring and into the horizontal flange of said angle-iron ring for removably holding said clamping ring in position and regulating the tension of the skin portion of said head; substantially as described.

In testimony whereof, I have signed my name to this specification in the presence of two subscribing witnesses.

THEODOR HEMBERGER.
